United States Patent Office.

CONRAD HARRIS AND PAUL W. ZOINER, OF CINCINNATI, OHIO.

Letters Patent No. 65,906, dated June 18, 1867.

CONVERTIBLE STOVE-DOOR AND FENDER.

The Schedule referred to in these Letters Patent and making part of the same.

TO WHOM IT MAY CONCERN:

Be it known that we, CONRAD HARRIS and PAUL W. ZOINER, both of Cincinnati, Hamilton county, Ohio, have invented a new and useful Convertible Stove-Door and Fender; and we hereby declare the following to be a full, clear, and exact description of the same, reference being had to the accompanying drawings, making part of this specification.

Our invention relates to a form of plate adapted either to serve as a fender to hide and shut in the ashes, or as a door to close the fire-front of the stove.

Figure 1 is a perspective view of a portion of the front and hearth of a stove provided with our improved convertible door and fender.

Figures 2 and 3 are vertical sections, showing our plate in its respective capacities of an air-tight door and of an ash-guard or fender.

Our convertible door and fender consists essentially of two unequal portions, A and B, whose margins, *a* and *b*, are at right angles to each other.

Of these portions the part A is adapted to occupy at discretion either the vertical opening C of the fire-front, or a horizontal depression, D, in the hearth; the portion B in the former case occupying a depression, E, in the hearth, and in the latter case closing the lower portion of the fire-opening sufficiently for the purpose of a fender.

A valuable peculiarity of our convertible door is that the same side is presented to view in each position, and consequently may be furnished with a convenient handle, F, and any suitable ornamentation, G.

We claim herein as new, and of our invention—

1. The convertible stove-door and fender, substantially as set forth.
2. The arrangement of convertible door and fender A B F, and hearth depressions D and E, substantially as represented and described.

In testimony of which invention we hereunto set our hands.

C. HARRIS,
P. W. ZOINER.
